UNITED STATES PATENT OFFICE.

GEORGE P. SCHMITT, OF OAKLAND, CALIFORNIA.

GAS-HEATED RADIATOR.

Application filed March 12, 1923. Serial No. 624,586.

To all whom it may concern:

Be it known that I, GEORGE P. SCHMITT, a citizen of the United States, residing at Oakland, in the county of Alameda and 5 State of California, have invented certain new and useful Improvements in Gas-Heated Radiators, of which the following is a specification.

This invention relates in general to heating stoves, and in particular to stoves of the gas-radiator type in which the source of heat is gaseous fuel, the hot gases circulating through the radiator for warming the surrounding air by direct radiation.

10 An object of the invention is to produce a radiator of the above type, in which the combustion is effected within the radiator and near the top thereof, and the resulting hot air and gases caused to pass downward 20 through one side of the radiating unit and up through the other side.

A further object is to provide such a radiator with a preheating chamber for warming the incoming air to the same.

25 Another object is to produce such a radiator in which the hot air and gases are superheated just before being discharged from the radiator.

And still another object is to provide such 30 a radiator with a damper to shunt hot gases immediately to the discharge flue, to dry out and heat the latter for the promotion of an immediate and effective induced draft. This latter object is of great importance in climates where there is considerable moisture 35 in the air, as the vent pipe to the atmosphere will not draw effectively unless it is thoroughly dry and free from moisture.

With the above and other objects in view, 40 the means by which I secure the efficiency of my invention will be fully set forth in the description and drawings of that embodiment of my invention which I have selected for illustration, and which is the best as 45 yet devised by me.

In the accompanying two sheets of drawings:

Figure 1 is a side elevation of a five-loop radiator constructed according to my in- 50 vention.

Figure 2 is an end elevation of the same.

Figure 3 is a vertical longitudinal section taken on the line A—A of Fig. 2.

Figure 4 is an enlarged fragmentary sec- 55 tion of one of the filler loops.

Figure 5 is a similar section of the middle loop.

Referring to the drawings and the figures thereof:—I have illustrated a five-loop radiator, though a greater or lesser number of loops may be used according to the space to be warmed. Each loop of the series is complete in itself, and has no circulatory connection with the other loops except at the top thereof. The separate loop units 60 are joined together by rods at the top and bottom as at 1 and 2.

The individual loop units open into each other at the extreme top forming a chamber which constitutes the superheater as will be 70 later described, and at the fire box immediately below the superheater which constitutes the combustion chamber. Otherwise the individual loop units are separate or insulated from each other and fitted together 75 in cement in any suitable way, such as by common male and female joints as shown.

Near the top of each loop is its fire box 3. The fire boxes are open toward each other so as to make a continuous fire box from end 80 to end of the radiator, closed at the ends by the walls 4 and 5, in one of which as 4, is a mica covered peep hole 6, and in the other of which is a door and hole 7 through which the gas may be lighted. In the lower part 85 of the fire box, immediately below the peephole 6 and the lighting hole 7, is the burner 8, which may be in the usual form of a perforated pipe as shown.

The lower half of the fire box is the pre- 90 heating chamber and is open to the circum- ambient air, which air, when the burner is lighted, rises and mixes with the gases of combustion. The mixed hot air and gases, rising against the top 9 of the fire box are 95 reflected and pass over the baffle-wall 10, and down to the bottom of the loop in the leg 11 thereof, and thence up in the other leg 17 and into the superheating chamber 12.

In the superheater the gases are further 100 heated by the top 9 of the fire chamber, and take a lateral and spiral course to the middle loop 18 and pass out at the flue 13. The effect of superheating is to vaporize entrained moisture, reheat the spent gases and increase 105 the draft.

In the middle loop 18 of the series, I preferably make an opening from the fire box to the upper portion of leg 17 as at 14, so that in starting the operation of the radi- 110

ator the hot air and products of combustion, may pass directly to the flue 13, thus starting an immediate suction through the radiator. This opening is closed by a valve 5 or damper 15, after the circulation is started. The damper 15 may be operated by a rod supported by the walls of this loop, and extending to the outside of the radiator and bent to form the operating handle 16 as indicated in Fig. 1. The baffle-wall 10 may be made somewhat higher opposite the opening 14, as seen in Fig. 5 to cause an increased draft effect when the damper is opened.

In operation, the issuing gas is lighted 15 and damper 15 opened as shown by the dot and dash lines in Fig. 5, to create an immediate draft as previously explained. In the interim, the flame of the burner impinging upon the sidewalls of the continuous 20 fire box, has caused the said walls to become hot, thus starting the preheater to function efficiently.

The damper is then closed and complete circulation effected. The cold air is drawn 25 into the preheater and heated by the walls thereof before the said air passes through the flame. The hot air and gases in the separate loops complete little more than a full circuit, as shown by the dot and dash 30 arrows, and collect in the superheater and are again heated by the flame impinging on the division wall 9, thence the horizontal column of moving products of combustion pass to and through the vent 13 to the atmosphere.

It will be observed that the radiator when in use, not only heats the room but causes a constant ventilation of the same as well.

From the foregoing description taken in 40 connection with the accompanying drawings, the advantages of the construction and method of operation will be readily understood by those skilled in the art to which the invention appertains, and while I have 45 described the principle of operation, together with the device which I now consider to be the best embodiment thereof, I desire to have it understood that the device shown is merely illustrative and that 50 such changes may be made when desired, as fall within the scope of the appended claims.

Having thus described my invention, I claim as new and desire to secure by Letters Patent:

55 1. In a stove of the gas-radiator type, a

radiating unit having a fire box near the top thereof and a superheating chamber above said fire box, the chamber being open for circulation.

2. In a stove of the gas-radiator type, a 60 radiating unit having a burner, fire box and discharge flue near the top thereof and having an opening from said fire box direct to the discharge flue, and a damper adapted to close the said opening.

65 3. A stove of the gas-radiator type composed of separate radiating units connected together, and each unit having a fire box near the top thereof, with an open bottom, the said bottoms forming one continuous 70 opening to the atmosphere.

75 4. A stove of the gas-radiator type composed of separate radiating units connected together, and each unit having a fire box near the top thereof with an open bottom, the said fire boxes opening into each other to form a continuous fire box from end to end of the radiator with a continuous open bottom.

80 5. A stove of the gas-radiator type composed of separate radiating units connected together, and each unit having a fire box near the top thereof, and a superheating chamber immediately above said fire box.

85 6. A stove of the gas-radiator type composed of separate radiating units connected together, and each unit having a fire box near the top thereof, and a superheating chamber immediately above said fire box, the said fire boxes opening into each other 90 to form a continuous fire box and the said superheating chambers opening into each other to form a continuous superheating chamber.

95 7. A stove of the gas-radiator type, comprising a burner, a combustion chamber, a superheating chamber, a preheating chamber and circulating tubes leading from the combustion chamber to the superheating chamber, the latter provided with an outlet for the products of combustion, the burner being positioned in the preheating chamber and which latter also forms the air inlet, the combustion chamber being positioned between the preheating and superheating chambers, and the latter chamber being the uppermost part of the stove.

100 In testimony whereof I affix my signature.

GEORGE P. SCHMITT.
